KNITTING MACHINE

Stanley R. Shelmire, Laconia, N. H., assignor to
 Scott & Williams, Incorporated, Laconia, N. H.,
 a corporation of Massachusetts

Application February 8, 1952, Serial No. 270,600

13 Claims. (Cl. 66—111)

1

This invention relates to knitting machines and has particular reference to an improved latch opener arrangement.

In the majority of knitting machine operations, the latches of latch needles are properly controlled by the stitch loops which are on the needles. Under certain circumstances, however, some or all of the needles may, at times, be devoid of loops so that the latches are free to take arbitrary positions. Provisions are sometimes made for guarding the latches to insure that they remain in proper positions but, at other times, the guards may not be provided at critical positions inasmuch as during different phases of operation the latches may be required to be either opened or closed at the same needle positions. Latch openers of mechanical type have been heretofore provided but they require controls of special types and must sometimes be associated with other elements for the purpose of insuring proper needle approach to the latch openers which, particularly in the case of fine gauge machines, must be very accurately positioned. For example reference may be made to the patent to Oberholtzer, No. 2,557,137, dated June 19, 1951. In the arrangement illustrated in this Oberholtzer patent, provision is made for insuring that needles approach a latch opener at a proper height so that the point of the latch opener may enter behind the latch for proper opening operation. If the needle is at an incorrect height, it is possible that the latch opener would engage the shank or hook of the needle thus breaking the needle and causing considerable damage. As will be evident from said Oberholtzer patent, mechanically elaborate devices are required for the control of the latch opener and the needle leveler.

Difficulty has been experienced often in the case of fine gauge machines in adjusting latch openers, since the needle hooks are so small that, though the setting may appear correct, there may be sufficient mechanical interference between the latch openers and the needles to wear or burr the needles so that yarn fibres may be damaged to such an extent as to produce imperfect fabric.

Mechanical latch openers are usually held in action by springs so that they may swing away from the needles if contacted by an exceptionally stiff latch or misaligned needle, and in such a case several needles might pass with closed latches before the latch opener could spring back to its operative position. The expected result would be a failure to properly begin knitting and

possible damage to several needles, sinkers or other knitting elements.

When latches are opened by mechanical means, they have, at times, a tendency to rebound and it is therefore generally considered necessary to use a latch opener which is long enough to prevent them from again closing until their needles can be moved to a position where they may be held open by a latch guard.

- 5 10 15 20 25 30 35
- 2 In accordance with the present invention, a simple latch opening device of pneumatic type is provided. A blast of air is directed against the hook of the needle in the general direction of the needle length, or in some other appropriate direction, and this blast of air, acting on the spoon of the latch, will cause it to open in reliable fashion. Preferably, the blast is maintained until the needle moves to such position that a latch guard takes over the duty of insuring that the latch properly remains open. The result is that all latches are reliably opened (unless unusually stiff), latch rebound is prevented by having the air blast act during a sufficient extent of needle movement, and all possibility of mechanical damage is avoided.

The pneumatic opening arrangement has, furthermore, the function of easily detecting defective latches which are too stiff to open properly. If the machine is turned by hand while the air blast is acting, its failure to open latches of any needles will lead to their being easily seen and replaced.

While the invention has more general aspects, it is particularly useful in connection with a knitting machine of the superposed cylinder type. As applied to such a machine, a current of air is directed into the slots of an upper cylinder with the result that the air escapes from the open lower ends of these slots and is thereby directed axially against the upper hook of each needle the latch of which is required to open.

While the latch opening arrangement constituting the present invention will be particularly described in connection with the operations involved in the formation of a press-off draw thread, it will become evident that the latch opening arrangement is of more general application and may, in fact, be applied to knitting machines of the single cylinder type.

When stitches have been pressed off during

downward movement of needles, there exists the possibility, unless some means is present to insure inward movement of the fabric, that the pressed-off stitches may be caught by the needles during a subsequent rise with resultant damage to the needles or to the fabric or may form a tuck-like stitch which, in the case of formation of a draw thread, would prevent subsequent withdrawal of the draw thread. In accordance with the present invention this possibility is avoided by providing an air blast against the freed stitches to move them inwardly prior to rise of the needles.

The broad objects of the present invention relate to the attainment of the latch opening and pressed-off stitch positioning in accordance with the foregoing. These and other objects particularly relating to details of construction and operation will become apparent from the following description read in conjunction with the accompanying drawing, in which:

Figure 1 is a fragmentary axial section through the adjacent ends of the cylinders of a superposed cylinder type of machine, the section being taken in the region in which latch opening occurs and specifically at the position indicated by the section line 1—1 in Figure 2, there being also illustrated diagrammatically in Figure 1 the means for controlling the air flow;

Figure 2 is a fragmentary interior development of the cams controlling needle movements in the vicinity of the latch opening position showing, additionally, a latch guard and certain openings therein for the passage of air; and

Figure 3 is an enlarged fragmentary axial section showing the latch guard and the air openings therethrough.

The lower and upper cylinders of a superposed cylinder type of machine are indicated, respectively, at 2 and 4. In respective slots 6 and 8 in the lower and upper cylinders there are arranged to slide lower sliders 10 and upper sliders 12 which control the movements of double-ended needles 14 of conventional type with which there cooperate the lower sinkers 18 and the verges 20. The remaining portions of this type of machine need not be described in detail since they are conventional except for the latch opening arrangement which will be described.

The machine may be considered to be of the two-feed type which, among other operations, is designed to provide a press-off draw thread. As is known, such draw thread is produced with knitting occurring on alternate needles in the upper cylinder while needles in the lower cylinder also knit at the main feed, then rise to clear their latches, and are then depressed at the auxiliary feed of the machine to cast off the stitches so drawn while the needles in the upper cylinder hold their stitches. The needles in the lower cylinder, then without stitches, are raised again to a clearing level and pass again through the main feed cam arrangement for the seizure of yarn. In Figure 2 there is illustrated at 22 the auxiliary feed stitch cam. As the lower cylinder needles are lowered by this stitch cam's action on their sliders the stitches held under the latches of the needles are cast off. The lower sliders are then raised by the successive cams 24 and 26 to clearing level. During this rise, the latches must be opened in preparation for the seizure of the yarn at the main feed. The latch opening has heretofore generally been accomplished at this time through the use of mechanical latch openers such as disclosed in said Oberholtzer patent.

The path taken by the upper ends of the hooks of the lower cylinder needles during the rise over cams 24 and 26 is indicated at A in Figure 2. A latch guard 30 is provided which, when the latches are properly opened, will maintain the latches open following the completion of rise over the cam 26. As indicated in Figure 1, this latch guard is provided with a sharp lower edge, indicated at 31, so that if a latch is only partially opened it will be fully opened as the needle rises to overlap the latch guard.

In accordance with the present invention, use is made of the fact that each slot 8 in the upper cylinder is in axial alignment with the needle corresponding thereto in the lower cylinder, and as the needle is rising along the path A the upper end of the needle is quite close to the lower end of its corresponding slot 8. At the same time, the upper slider in each of the slots 8 is riding with its lower butt at the upper welt level indicated at 28 in Figure 2 so that the portion of each slot 8 which does not contain a needle in the upper cylinder is cleared for the possible passage of air at the level of the latch guard 30.

The latch guard 30 is provided with a series of downwardly and inwardly sloping holes indicated at 32 in the circumferential region of approach of the needles to the latch guard along the path A. The outer ends of these holes 32 communicate with an elongated opening 34 in a manifold 36 provided with a bore 38. The bore 38 communicates with a tube 40 which is connected to an air supply line 44 through a valve 42 the stem 46 of which may be acted upon by the lever 48 controlled by a plunger 50 from the main cam drum of the machine to provide for flow of air at proper times during the machine operation.

Also connected to the tube 40 by a T 52 is a tube 54 terminating in a flattened, horizontally-extending nozzle 56 located as shown most clearly in Figure 2 to direct air radially inwardly across the upper ends of the hooks of needles in the lower cylinder where these needles are in their lowermost positions below or immediately following the lower end of cam 22 and prior to their rise over cam 24.

Desirably, there is also included in the air supply line a device 58 of conventional type, the stem 60 of which is held upwardly by air pressure so long as the supply pressure is adequate to produce proper blasts through the passages 32 and 56. If the supply fails, the stem 60 will drop and, by connection to the usual stop motion of the machine, will stop the machine before any damage occurs. This action may be effected by causing stem 60 in its upper position to maintain closed a switch 62 which is in series with an electromagnet 64, the secondary of a transformer 66, and a contact 67 engaging a lever 72 which is grounded. The electromagnet 64 when energized raises the left hand end of a pivoted armature 68 against the action of a spring 69 to maintain the armature extension 70 within the hook of a pivoted lever 72 urged clockwise, as viewed in Figure 1, by a light spring 73 but having its upper end engaged by an arm 74 acted upon by a strong spring 76. The arm 74 is connected to a shaft having an arm 77 connected by a link 78 to the conventional mechanical stop motion of the machine, i. e. to the mechanism which will release a connection to the driving pulley and/or stop a driving motor or otherwise effect stoppage of the machine. So long as the stem 60 is held raised by the supply pressure, the parts will occupy the positions illustrated in Figure 1. How-

ever, if the supply fails, the stem 60 will drop, opening switch 62 and deenergizing electromagnet 64. This, in turn, permits rocking of armature 68 to release extension 70 from lever 72 which may thereupon be rocked counterclockwise by the action of spring 76 which exerts a pull on link 78 to stop the machine. At the same time, the contact at 67 is opened in the secondary circuit of the transformer. When the pressure of the supply is reestablished, switch 62 will be closed but the electromagnet will not be reenergized until running of the machine is reestablished whereupon the parts are restored to the positions illustrated.

The operation may be described as follows:

During the phases of operation of the machine requiring latch opening, the valve 42 is opened to admit air to the bore 38 of the manifold, from the opening 34 of which the air flows through the openings 32 into the portions of the slots 8 below the upper sliders 12. These portions of the slots are circumferentially bounded by the latch guard 30 so that the lower ends of the slots form, in effect, tubular passages for the direction of air blasts upon the upper ends of the needles in the lower cylinder. The air blasts thus directed downwardly impinge upon the spoons of the latches of the needles driving the latches to open positions. As will be evident particularly from Figure 2, the blast on each needle begins to act when the needle is rising and approaching the latch guard. The blast thus provided insures that the latch will be opened before the needle hook rises to the level of the edge 31 of the latch guard. After the hook passes this level, the guard itself maintains the latch open and will fully open the latch in the event that the air blast has not moved the latch to its lowermost position. The use of a plurality of openings at 32 insures that the blast on each needle is of sufficient duration so that its latch will be opened and held opened until the latch guard takes over the function of maintenance of the open position.

While the slots in the upper cylinder are utilized in the arrangement just described to direct the air blasts in the direction of the lengths of the needles, it will be evident that the invention may be applied to machines of single cylinder type by the provision of means located above the needles for securing similar direction of the air blasts. Or the air blast may be directed outwardly towards the backs of the needle hooks and will thus open the latches, such an arrangement being adoptable also in the case of superposed cylinder machines in which the air may be directed outwardly between the cylinders. Various intermediate directions of the air blast may also be used for the same purpose.

At the same time as air is admitted to the openings 32, air is also directed through nozzle 56 against the stitches which will have been pressed off the needles in the lower cylinder, as these needles were lowered by cam 22, and which may be located above the needle hooks in such position as possibly to be engaged by the hooks as the needles next rise over cam 24. The blast of air from nozzle 56 will drive these stitches and the fabric inwardly sufficiently to prevent such engagement.

What is claimed is:

1. A knitting machine comprising independently movable latch needles, and means for directing a blast of air upon the hooks of the needles for opening the latches thereof.

2. A knitting machine comprising independently movable latch needles, a latch guard positioned to be overlapped by the needles during movements thereof, an opening in said latch guard, and means for directing air through said opening and upon the hook ends of the needles approximately in the direction of the lengths of the needles for opening the latches thereof prior to overlap of the latch guard by the needles.

3. A knitting machine comprising independently movable latch needles, a latch guard positioned to be overlapped by the needles during movements thereof, a plurality of openings in said latch guard, and means for directing air through said openings and upon the hook ends of the needles approximately in the direction of the lengths of the needles for opening the latches thereof prior to overlap of the latch guard by the needles.

15 4. A knitting machine comprising superposed slotted cylinders, independently movable latch needles mounted in the slots of one of said cylinders, and means for directing air into the slots of the other cylinder to provide a blast of air from the open ends of the last mentioned slots upon the hook ends of the needles approximately in the direction of the lengths of the needles for opening the latches thereof.

20 5. A knitting machine comprising superposed slotted cylinders, independently movable latch needles mounted in the slots of one of said cylinders, a latch guard substantially closing peripheral portions of the slots of the other cylinder and positioned to be overlapped by the needles during movements thereof, an opening in said latch guard for leading air into the slots of the second mentioned cylinder, and means for directing air through said opening into the last mentioned slots and thence from the open ends 25 of the last mentioned slots upon the hook ends of the needles approximately in the direction of the lengths of the needles for opening the latches thereof prior to overlap of the latch guard by the needles.

25 6. A knitting machine comprising superposed slotted cylinders, independently movable latch needles mounted in the slots of one of said cylinders, a latch guard substantially closing peripheral portions of the slots of the other cylinder and positioned to be overlapped by the needles during movements thereof, a plurality of openings in said latch guard for leading air into the slots of the second mentioned cylinder, and means for directing air through said openings 30 into the last mentioned slots and thence from the open ends of the last mentioned slots upon the hook ends of the needles approximately in the direction of the lengths of the needles for opening the latches thereof prior to overlap of the latch guard by the needles.

35 7. A knitting machine comprising superposed slotted cylinders, independently movable latch needles mounted in the slots of one of said cylinders, a latch guard substantially closing peripheral portions of the slots of the other cylinder and positioned to be overlapped by the needles during movements thereof, a plurality of circumferentially spaced openings in said latch guard for leading air into the slots of the second mentioned cylinder, and means for directing air 40 through said openings into the last mentioned slots and thence from the open ends of the last mentioned slots upon the hook ends of the needles approximately in the direction of the lengths of the needles for opening the latches thereof prior to overlap of the latch guard by the needles.

45 8. A knitting machine comprising superposed slotted cylinders, independently movable latch needles mounted in the slots of one of said cylinders, a latch guard substantially closing peripheral portions of the slots of the other cylinder and positioned to be overlapped by the needles during movements thereof, a plurality of circumferentially spaced openings in said latch guard for leading air into the slots of the second mentioned cylinder, and means for directing air 50 through said openings into the last mentioned slots and thence from the open ends of the last mentioned slots upon the hook ends of the needles approximately in the direction of the lengths of the needles for opening the latches thereof prior to overlap of the latch guard by the needles.

55 9. A knitting machine comprising superposed slotted cylinders, independently movable latch needles mounted in the slots of one of said cylinders, a latch guard substantially closing peripheral portions of the slots of the other cylinder and positioned to be overlapped by the needles during movements thereof, a plurality of circumferentially spaced openings in said latch guard for leading air into the slots of the second mentioned cylinder, and means for directing air 60 through said openings into the last mentioned slots and thence from the open ends of the last mentioned slots upon the hook ends of the needles approximately in the direction of the lengths of the needles for opening the latches thereof prior to overlap of the latch guard by the needles.

65 10. A knitting machine comprising superposed slotted cylinders, independently movable latch needles mounted in the slots of one of said cylinders, a latch guard substantially closing peripheral portions of the slots of the other cylinder and positioned to be overlapped by the needles during movements thereof, a plurality of circumferentially spaced openings in said latch guard for leading air into the slots of the second mentioned cylinder, and means for directing air 65 through said openings into the last mentioned slots and thence from the open ends of the last mentioned slots upon the hook ends of the needles approximately in the direction of the lengths of the needles for opening the latches thereof prior to overlap of the latch guard by the needles.

70 11. A knitting machine comprising superposed slotted cylinders, independently movable latch needles mounted in the slots of one of said cylinders, a latch guard substantially closing peripheral portions of the slots of the other cylinder and positioned to be overlapped by the needles during movements thereof, a plurality of circumferentially spaced openings in said latch guard for leading air into the slots of the second mentioned cylinder, and means for directing air 70 through said openings into the last mentioned slots and thence from the open ends of the last mentioned slots upon the hook ends of the needles approximately in the direction of the lengths of the needles for opening the latches thereof prior to overlap of the latch guard by the needles.

75 12. A knitting machine comprising superposed slotted cylinders, independently movable latch needles mounted in the slots of one of said cylinders, a latch guard substantially closing peripheral portions of the slots of the other cylinder and positioned to be overlapped by the needles during movements thereof, a plurality of circumferentially spaced openings in said latch guard for leading air into the slots of the second mentioned cylinder, and means for directing air 75 through said openings into the last mentioned slots and thence from the open ends of the last mentioned slots upon the hook ends of the needles approximately in the direction of the lengths of the needles for opening the latches thereof prior to overlap of the latch guard by the needles.

prior to overlap of the latch guard by the needles.

8. A knitting machine comprising independently movable latch needles, means for moving needles lengthwise to press off stitches carried thereby and for thereafter reversing the lengthwise movements of the needles, and means for directing a blast of air against the fabric to move the pressed off stitches out of the path of the needles in their last mentioned movements to prevent engagement of the pressed off stitches by the needles.

9. A knitting machine comprising independently movable latch needles, means for moving needles lengthwise to press off stitches carried thereby and for thereafter reversing the lengthwise movements of the needles, means for directing a blast of air against the fabric to move the pressed off stitches out of the path of the needles in their last mentioned movements to prevent engagement of the pressed off stitches by the needles, and means for effecting opening of the needle latches following the action of the blast of air on the fabric.

10. A knitting machine comprising independently movable latch needles, means for moving needles lengthwise to press off stitches carried thereby and for thereafter reversing the lengthwise movements of the needles, means for directing a blast of air against the fabric to move the pressed off stitches out of the path of the needles in their last mentioned movements to prevent engagement of the pressed off stitches by the needles, and means for directing a blast of air upon the hook ends of the needles approximately in the direction of the lengths of the needles for opening the latches thereof following the action of the blast of air on the fabric.

dles for opening the latches thereof following said action of the first mentioned blast of air on the fabric.

11. A knitting machine comprising independently movable latch needles, means for directing a blast of air upon the hooks of the needles for opening the latches thereof, and means for stopping the machine upon failure of the supply of air for said blast.

10 12. A knitting machine comprising independently movable latch needles, means for moving needles lengthwise to press off stitches carried thereby and for thereafter reversing the lengthwise movements of the needles, means for directing a blast of air against the fabric to move the pressed off stitches out of the path of the needles in their last mentioned movements to prevent engagement of the pressed off stitches by the needles, and means for stopping the machine 15 upon failure of the supply of air for said blast.

13. A knitting machine comprising independently movable latch needles, and means for directing a blast of air upon the hooks of the needles for opening the latches thereof and for 20 maintaining the latches open against rebound.
